UNITED STATES PATENT OFFICE.

HAROLD D. WATERHOUSE, OF WEST HARTFORD, CONNECTICUT.

CURRENT-DISTRIBUTER FOR INTERNAL-COMBUSTION ENGINES.

1,379,584.

Specification of Letters Patent.

Patented May 24, 1921.

Application filed October 23, 1919. Serial No. 332,748.

To all whom it may concern:

Be it known that I, HAROLD D. WATERHOUSE, a citizen of the United States, residing at West Hartford, in the county of 5 Hartford and State of Connecticut, have invented a new and useful Improvement in Current-Distributers for Internal-Combustion Engines, of which the following is a specification.

10 This invention relates to the construction of those devices which are provided for distributing electric current at the proper intervals to the spark plugs of the several cylinders of internal combustion engines, and 15 more particularly such distributers as are used on Ford automobiles.

The object of the invention is to provide a device of this character which is simple and cheap to construct and that can be readily 20 applied to the time shafts of Ford motors without any change in the present construction of the shafts and casings and which will obviate the use of vibrating induction coils, eliminate electrical lag and render the 25 timing and certainty of ignition uniform, and thus raise the efficiency of ignition in the motors of these cars to that of the motors of more expensive makes of cars.

Figure 1 of the accompanying drawings 30 shows a central section of a device which embodies the invention. Fig. 2 shows a front elevation with a portion of the casing broken away. Fig. 3 shows a side elevation with a portion of the casing cut in section. 35 Fig. 4 is a perspective view of the operative parts of the device, the casing being omitted, with a diagrammatic representation of the electrical circuit in which it is used. Fig. 5 is a plan of the cam which causes the make 40 and break of the primary induction circuit.

The device is designed to be slipped upon the regular motor time shaft by which it is supported and operated close to the motor case, and to permit this it is provided with a 45 metallic sleeve 1 having a key-way 2 adapted to slide upon and be keyed to the shaft in present use so as to rotate therewith.

The distributor casing, which does not rotate with the time shaft and sleeve, comprises a shell of insulating material 3 with a metallic end plate 4 secured over the open end of the shell. The end plate has a hub 5 which forms a bearing on the sleeve at one end, and a metallic bushing 6 is inserted 55 into the shell for providing a bearing on the sleeve at the other end. An eye 7 is formed

in the shell for the connection of the end of the spark advancing and retarding rod. Threaded binding posts 8 are secured in the annular rim of the shell at the desired 60 localities. These posts extend to the inner peripheral wall of the shell, and to their outer ends the circuit wires 9 leading to the several spark plugs 10 are connected. A threaded binding post 11 is secured in the 65 front of the shell near the lower edge. This post has a terminal 12 that extends to the inner face wall of the shell, and to its outer end the circuit wire 13 from the high tension secondary winding 14 of the induction coil 70 is connected.

Over an opening in the front of the shell is a cover 15 of insulation that is removably held in position by a leaf spring 16 which is designed to have its lower end thrust under 75 a fixed loop 17 and its upper end under a loop 18 that can be swung onto or off from the end of the cover holding spring. In the cover is a threaded binding post 19 with a terminal point 20 in the inside. To the outer 80 end of this post a wire 21 from the low tension primary winding 22 of the induction coil is connected.

A conducting spring arm 23 is fastened at one end to the shell opposite the cover, preferably by two screws 24 with a tilting plate 25 between the arm and wall of the shell, so that by turning in and out the proper screws the exact position of the free end of the arm may be determined. A conducting spring 90 finger 26 is fastened at one end to the free end of the spring arm. The tip of this finger is restricted in its outward movement by a stop 27 on the arm and it bears a contact point 28 which is adapted to make and break 95 connection with the point 20 of the primary circuit binding post 19 mounted on the cover. The spring arm is connected by a wire 30 with a ground or with the source of electric current, as generator 29, and the 100 source of current connected by a wire 31 with an end of the primary induction coil winding. Fastened to the back of the free end of the spring arm is a foot 32. All of the above described parts are relatively stationary, that is, they do not rotate when the device is in operation but they are capable of oscillation for advancing or retarding the times of ignition.

Fixed upon the sleeve 1 and rotating therewith is an insulating block 33, and loosely mounted on the sleeve close to the face of

the block are two annular plates 34 and 35 which are spaced a small distance apart. The outer plate 35 is slotted about its edge to form four segmental sections and each of these sections is carried inward in two steps toward the inner plate 34 to which the inner ends of the segments are secured. This provides a cam having four segmental planes 36 in the plane of the outer plate, four segmental planes 37 intermediate the inner and outer plates, and four segmental planes 38 which are secured to and are substantially in the plane of the inner plate. The elevations of these segmental planes are such that during the rotation of the time shaft, sleeve, block and these plates the foot 32 on the spring arm 23 will be pressed outward by the outer plane 36 sufficiently to put the spring arm under tension and cause the contact point 28 on the spring finger to engage with the contact point 20 of the binding screw 19 and close the primary circuit. The foot will then drop off from the end of the plane 36 into space and permit the arm and finger to rapidly vibrate and thus open and close the primary circuit many times quickly. Then, after allowing the required vibrations of the spring arm to produce the desired makes and breaks in the primary circuit, the foot will rest against the intermediate plane 37 and hold the arm from vibration. Finally the foot will rise on the following plane 36 and again place the spring arm under tension and close the primary circuit preparatory to dropping off the end of that plane and again permitting the arm to vibrate and open and close the primary circuit.

To cause the rotation of the cam formed of these plates, a spring plunger 39 is arranged in the block which is fixed to the sleeve, so that its outer end projects into an opening in the inner plate 34. This opening in the inner plate is formed by punching a tongue 40 outward from the plate, which tongue is inclined over the end of the spring plunger. When the sleeve and block are rotating forwardly the spring plunger engages the wall of the opening in the inner plate and carries the cam plates with the block. If for any reason the sleeve and block are rotated backward, the spring plunger rides under the inclined tongue on the inner plate and is pressed inward thereby so that the block will turn without carrying the cam plates.

On one face of the rotatory block is a conducting ring 41 which at one locality has an outwardly extending finger 42 with a brush 43 that is bent around the edge of the block into such position that as the block rotates this brush passes close to the ends of the binding posts 8 to which the wires of the secondary circuit that lead to the spark plugs are connected. This conducting ring 65 is also in such a position that it is close to

the end of the terminal 12 of the binding post 11 to which the secondary coil is connected.

With this device a very rapid vibration of the spring arm is produced at regular intervals for the purpose of opening and closing the primary circuit. This vibration is so timed that the current induced in the secondary circuit of the induction coil is sent through the device to one or the other of the 70 spark plugs, depending upon the position of the brush 43 of the rotatable ring 41 which is in the secondary circuit. The structure can be readily slipped upon the shaft of the ordinary Ford motor and it is easily adjusted so that it will surely operate at the required moment to cause a shower of sparks to cross the terminals of the several spark plugs at the desired time to effect the ignition 80 of the gas in the cylinders. 85

The invention claimed is:

1. A current distributor for internal combustion engines comprising a sleeve adapted to be secured to a rotatory shaft, an insulating casing rotatably mounted on the sleeve, 90 a binding post with a conducting contact mounted on the casing, a resilient metallic arm with one end secured to the casing, an insulating block secured to the sleeve, a cam connected with the block and adapted at intervals to place the resilient arm under tension and cause the repeated engagement of the arm with the binding post contact, binding posts on the casing, and a conductor rotatable with the block and adapted to 95 sequentially electrically communicate with the last mentioned binding posts.

2. A current distributor for internal combustion engines comprising a sleeve adapted to be secured to a rotatory shaft, an insulating 105 casing rotatably mounted on the sleeve, a binding post with a conducting contact mounted on the casing, a spring arm mounted on the casing, a spring finger with a conducting contact mounted on said arm, an 110 insulating block secured to the sleeve, a cam connected with the block and adapted at intervals to place the spring arm under tension and cause the engagement of the contact on the spring finger with the binding post 115 contact, binding posts on the casing, and a conductor rotatable with the block and adapted to sequentially electrically communicate with the last mentioned binding posts.

3. A current distributor for internal combustion engines comprising a sleeve adapted to be secured to a rotatory shaft, an insulating casing rotatably mounted on the sleeve, a binding post with a conducting contact mounted on the casing, a resilient arm with 125 one end secured to the casing, a foot extending from the free end of said arm, a spring finger with one end secured to the free end of said arm, an insulating block secured to the sleeve, a cam connected with the block 130

and adapted at intervals to engage said foot and place the spring arm under tension and cause the engagement of the spring finger thereon with the binding post contact, binding posts on the casing, and a conductor rotatable with the block and adapted to sequentially electrically communicate with the last mentioned binding posts.

4. A current distributor for internal combustion engines comprising a sleeve adapted to be secured to a rotatory shaft, an insulating casing rotatably mounted on the sleeve, a binding post with a conducting contact mounted on the casing, a spring arm having a conducting contact and secured to the casing by a tilting connection, an insulating block secured to the sleeve, a cam connected with the block and adapted at intervals to place the spring arm under tension and cause the engagement of the contact thereon with the binding post contact, binding posts on the casing, and a conductor rotatable with the block and adapted to sequentially electrically communicate with the last mentioned binding posts.

5. A current distributor for internal combustion engines comprising a sleeve adapted to be secured to a rotatory shaft, an insulating casing rotatably mounted on the sleeve, a binding post with a conducting contact mounted on the casing, a spring arm with a conducting contact mounted on the casing, a foot extending from the free end of said arm, an insulating block secured to the sleeve, a cam connected with the block, said cam having steps in different planes and adapted at intervals to engage said foot and cause the spring arm to vibrate and engage the contact thereon with the binding post contact and at intervals retain the arm from vibration, binding posts on the casing, and a conductor rotatable with the block and adapted to sequentially electrically communicate with the last mentioned binding posts.

6. A current distributor for internal combustion engines comprising a sleeve adapted to be secured to a rotatory shaft, an insulating casing rotatably mounted on the sleeve, a binding post with a conducting contact mounted on the casing, a spring arm with a

conducting contact mounted on the casing, an insulating block secured to the sleeve, a cam loosely mounted on the sleeve, means connecting the cam and block so the cam will rotate with the block in one direction only and at intervals place the spring arm under tension and cause the engagement of the contact thereon with the binding post contact, binding posts on the casing, and a conductor rotatable with the block and adapted to sequentially electrically communicate with the last mentioned binding posts.

7. A current distributor for internal combustion engines comprising a sleeve adapted to be secured to a rotatory shaft, an insulating casing rotatably mounted on the sleeve, a binding post with a conducting contact mounted on the casing, a spring arm with a conducting contact mounted on the casing, an insulating block secured to the sleeve, a cam rotatable in one direction only with the block and adapted at intervals to place the spring arm under tension and cause the engagement of the contact thereon with the binding post contact, means for preventing the cam from rotating reversely with the block, binding posts on the casing, and a conducting ring secured to the block, said ring having a brush that is adapted to sequentially electrically communicate with the last mentioned binding posts.

8. A current distributor for internal combustion engines comprising a sleeve adapted to be secured to a rotatory shaft, an insulating casing rotatably mounted on the sleeve, a cover detachably secured to the casing, a binding post with a conducting contact mounted on said cover, a spring arm with a conducting contact adjustably mounted on the casing inside of said cover, an insulating block secured to the sleeve, a cam connected with the block and adapted at intervals to place the spring arm under tension and cause the engagement of the contact thereon with the binding post contact, binding posts on the casing, and a conductor rotatable with the block and adapted to sequentially electrically communicate with the last mentioned binding posts.

HAROLD D. WATERHOUSE.
